(57) **CLAIM**

The ornamental design for a charger for a mobile communication terminal, as shown and described.

DESCRIPTION

FIG. 1 illustrates a perspective view of the charger for a mobile communication terminal;

FIG. 2 illustrates a front side of the charger for a mobile communication terminal;

FIG. 3 illustrates a rear side of the charger for a mobile communication terminal;

FIG. 4 illustrates a left side of the charger for a mobile communication terminal;

FIG. 5 illustrates a right side of the charger for a mobile communication terminal;

FIG. 6 illustrates a top side of the charger for a mobile communication terminal; and,

FIG. 7 illustrates a bottom side of the charger for a mobile communication terminal.

1 Claim, 6 Drawing Sheets
